UNITED STATES PATENT OFFICE

SAMUEL SHAFER, JR., OF MILWAUKEE, WISCONSIN, ASSIGNOR TO CHAIN BELT COMPANY, OF MILWAUKEE, WISCONSIN, A CORPORATION OF WISCONSIN

BRAKE-CONTROL MECHANISM FOR CONCRETE MIXING AND OTHER MACHINES

Application filed February 1, 1927. Serial No. 165,171.

In the operation of concrete mixing machines it is customary to load the revolving drum in which concrete is mixed by means of a pivoted skip that rests upon the ground to receive its load and is then elevated to such position that the charge will slide into the interior of the mixing drum. The movements of the skip are ordinarily controlled by cables that are connected with the skip and pass to winding drums, which are driven through gearing connected with a suitable source of power. The descent of the skip is usually controlled by means of a brake that retards the unwinding of the cables, this brake being manually controlled. It sometimes happens that through inattention or inefficiency of the operator the skip is allowed to descend without being controlled by the brake, and this has resulted in the injury of workmen, immediate damage to the apparatus, and the entanglement of the cables, due to the rapid rotation of the drums on which they are supported, which latter is an almost inevitable result of too rapid descent of the loaded skip, and means trouble and delay in properly restoring the cables to positions upon the drums and perhaps serious injury to the machine if attempt be made to elevate the skip before the cables have been properly replaced.

My invention has for its object to provide automatic means for controlling the descent of the skip in a machine such as described and for controlling the movements of a piece of mechanism typified by the loading skip of a concrete mixing machine, and one embodiment thereof is illustrated in the accompanying drawings and will be described in the specification to follow.

In the drawings Fig. 1 is a side view of a concrete mixing machine to which my invention is applied.

Fig. 2 is an end view of the same.

Fig. 3 is an end view of the brake control mechanism drawn to a larger scale than Figs.

1 and 2 and with the dash pot thereof broken away to show the interior thereof.

In the accompanying drawings I have shown my invention applied to a concrete mixing machine of well known construction, in which A represents a rotatable drum wherein the concrete is mixed, B the loading skip pivotally supported on a shaft *b* mounted in the framework C of the machine. The movements of the skip, from its lower charge-receiving position, represented in full lines, to its elevated discharging position, indicated in dotted lines, are controlled by cables D, which are wound upon drums *d*, supported on a cross shaft mounted in the upper part of the framework C. A large wheel E is supported on the same shaft as that carrying the drums *d*, and to this is attached a cable F that extends to the winding drum G. The drum G is rotated to wind the cable F thereon and elevate the skip to discharging position, from a power shaft H, through suitable gearing including a clutch I, controlled by an operating lever J, the lever being adapted for manual control.

Associated with the cable-winding drum G is a brake wheel or drum K with which engages a brake band L controlled by a lever M, which is likewise adapted for manual control. The parts thus far described are of well known construction and, so far as my present invention is concerned, they may be of the specific form shown or they may differ therefrom quite widely in details of construction and in arrangement.

The shaft *b* to which the skip is secured is represented as provided with a crank arm 2, located on the same side of the machine as is the brake lever M. A dash-pot 3 is connected with the brake lever, as by a pivot 4. The dash-pot, which may be of usual construction, has a piston 5 that is connected by a piston rod 6 with the crank arm 2, the pivotal connection of these parts being indicated at 7.

An air port 8 opens to the external atmosphere through the cylinder of the dash-pot on that side of the piston 3 that is toward the brake lever. A needle valve 9 is arranged 5 to control the size of this port. It will thus be seen that there is interposed a dash-pot between a part that moves as the skip is raised and lowered and the brake lever. As the skip is raised to discharging position the 10 crank arm 2 is moved in the direction of the arrow, Fig. 1, moving the piston 5 of the dash-pot downward or in a direction away from the brake lever, and as it so moves air is drawn into the cylinder of the dash-pot 15 through the port 8. As the skip moves slowly as it is elevated from its loading position to that of discharge there will be abundant time for the cylinder of the dash-pot to fill with air, through the port 8, without perceptibly opposing the upward movement of the skip. After the skip reaches the position 20 to discharge, the driving connection with the power shaft is broken, through the manipulation of the lever J that controls the clutch, 25 and the skip may then be momentarily held in its elevated position, either by the usual spring 10, or manually by moving the handle M to apply the brake. But a light application of the brake is required for this purpose 30 as the center of gravity of the skip is so little to one side of the vertical plane that includes the pivot b. Instead of providing for a short 35 rest or dwell of the skip in its raised discharging position the apparatus may be so designed that the skip will begin its downward movement as soon as the driving connection with the power shaft is broken through the manipulation of the clutch. As the skip moves downwardly the shaft b is 40 rotated and the piston 5 is moved upwardly within the cylinder of the dash-pot compressing the body of air between the piston and the upper end of the cylinder. The pressure thus created acts upon the cylinder, and 45 through its pivotal connection 4 with the lever M, upon such lever, to set the brake, and the more rapid the descending movement of the skip the greater the force with which the brake is applied. If the portion of the cylinder 50 to the rear of the piston 5 were closed air tight, it is apparent that the brake would very soon be so tightly set as to hold the skip suspended against further downward movement; but as the port 8 allows for a leakage 55 of the air within the cylinder, the pressure therein is gradually reduced, with a corresponding reduction of the pressure of the 60 brake upon the drum K and thus the brake is kept applied with just enough pressure to allow the skip to descend safely.

The relations of the various parts are such that the leakage of air through the port 8 will be just sufficient to maintain an air pressure within the dash-pot that will set the 65 brake to such a degree as will allow the skip

to descend at the desired speed. If it should be found that the descent is too slow the needle valve 9 will be adjusted to enlarge the port; while on the other hand if the descent be too rapid the size of the port will be reduced by such valve. 70

I have described means by which the descent of the loading skip is automatically controlled and this is done through the application of a brake associated with the winding drum of the cable that moves the skip. The lever with which the dash-pot is connected is, as has been stated, a lever capable of manual control, and this permits the operator of the apparatus to govern the descent of the skip quite irrespective of the automatic apparatus that has been described, allowing him either to set the brake, at any point in the descent of the skip, with a force sufficient to immediately arrest the movement thereof, or to accelerate the descent of the skip beyond the speed contemplated by the operation of the automatic apparatus. 80

While I have described my invention applied to a concrete mixing machine it is not, as has been herein intimated, limited in its useful applications to that particular use, and I wish it understood that my invention is not limited beyond what is expressed in the claims hereof. 90

What I claim is:

1. The combination with a moving part of an apparatus, a brake for controlling its movements in one direction and a manually operated lever for controlling the brake, of connections between the moving part and the brake through which the latter is automatically controlled by the movements of the former and in accordance with its speed, the brake being manually operable irrespective of the automatic operating means. 100

2. The combination with a moving pivoted part of an apparatus, a brake for controlling its movements and a manually operated brake lever, of connections between the said pivoted part and the brake lever through which the brake is operated as the pivoted part moves. 110

3. The combination with a pivoted part of an apparatus, a cable through which it is elevated, the pivoted part returning by gravity, a brake for controlling the return movements of the said part and a manually operated brake lever, of an arm movable with the pivoted part and a connection between the said arm and the brake lever including a dash-pot. 120

4. The combination with a pivoted movable part of an apparatus, cables by which it is raised, power-driven winding mechanism for the cables, a brake by which the return or lowering movements of the said movable part are controlled and a manually operated hand lever for the brake, of a crank arm connected so as to move with the said movable part and connections between the said crank 125 and the brake 130

arm and the brake lever including a dash-pot.

5. The combination with a pivoted movable part of an apparatus, cables by which it is moved, power-driven winding mechanism for the cables, a drum by which the return or lowering movements of the movable part are controlled, and a manually operated hand lever for the brake, of a crank arm movable with the said movable part, a dash-pot having pivotal connection with the brake lever and a rod carrying the piston of the dash-pot having pivotal connection with the crank arm, the restricted air port of the dash-pot being in that end thereof toward the brake lever.
